(57) **CLAIM**

The ornamental design for a playground transfer loop for connecting a climber and slide, substantially as shown and described.

DESCRIPTION

FIG. 1 is a perspective view from above of a playground transfer loop for connecting a climber and slide according to the present invention and shown positioned in the exemplary environment of a playground structure;

FIG. 2 is a front side elevation view of the playground transfer loop for connecting a climber and slide of FIG. 1; FIG. 3 is a rear side elevation view of the playground transfer loop for connecting a climber and slide of FIG. 1; FIG. 4 is a right side elevation view of the playground transfer loop for connecting a climber and slide of FIG. 1; FIG. 5 is a left side elevation view of the playground transfer loop for connecting a climber and slide of FIG. 1; FIG. 6 is a top plan view of the playground transfer loop for connecting a climber and slide of FIG. 1; and, FIG. 7 is a bottom plan view of the playground transfer loop for connecting a climber and slide of FIG. 1.

The broken lines are for illustrative purposes and represent environmental structure and unclaimed portions of the invention and therefore form no part of the claimed design.

1 Claim, 7 Drawing Sheets
